WEIGHING SCALE

William Y. Hutchinson, Chicago, and Walter P. Kushmuk,
Niles, Ill., assignors to Continental Scale Corporation,
Chicago, Ill.

Filed Mar. 22, 1972, Ser. No. 337,233

Term of patent 14 years

Int. Cl. D10—04

U.S. Cl. D52—10 R

FIG. 1

FIG. 2

FIG. 3

FIG. 1 is a front elevational view of a weighing scale showing our new design;

FIG. 2 is a right side elevational view thereof, the left side being a mirror image thereof;

FIG. 3 is a top plan view thereof.

We claim:

The ornamental design for a weighing scale, as shown and described.
